UNITED STATES PATENT OFFICE

RUTH F. ALBERT, OF NEW YORK, N. Y.

GARMENT

Application filed March 22, 1930. Serial No. 438,029.

This invention relates to an improvement in garments intended for feminine wear and has for its object to provide a type of garment which may be constructed for either under or outer wear, and which, by reason of its construction, will be extremely simple to manufacture with a consequent decrease in the cost thereof; well fitting, and pleasing in appearance.

10 A further object of the invention is to provide a garment which will meet the requirements of smoothness and symmetry which are requirements of all garments that are in vogue at the present time. Its construction is such that the garment fits extremely smoothly, permitting the use of snug-fitting outer garments, should the garment of my construction be used as an undergarment.

20 A feature of the invention resides in the use of but few seams required in the manufacture of the garment, thus greatly decreasing the sewing operations required and consequently resulting in a decrease in manufacturing cost.

25 With these and many other objects in view, I have devised the particular arrangement of parts described hereinafter and more particularly pointed out in the claims appended hereto.

30 Reference is to be had to the accompanying drawings forming a part hereof in which

Figure 1 is a plan view of the main blank or body portion which forms a part of one form of my improved garment;

35 Figure 2 is a plan view of an inserted section of fabric which, when combined with the body portion disclosed in Figure 1 serves to make up the garment;

40 Figure 3 is a view showing the parts disclosed in Figures 1 and 2 in position ready for seaming together to complete the assembly;

45 Figure 4 is a rear view of the completed garment;

Figure 5 is a front view of the same;

Figure 6 is a view of a body portion employed in the manufacture of a skirted garment such as a slip, an outer dress, or the like;

Figure 7 is a view of the added skirt section;

Figure 8 is a rear view of the completed garment, showing the fabric sections disclosed in Figures 6 and 7 seamed together; 55 and

Figure 9 is a front view of the finished garment.

Throughout the various views of the drawings, similar reference characters designate 60 similar parts.

Referring to the embodiment of my invention disclosed in Figures 1 to 5 inclusive. Here is shown a type of garment commonly known as an envelope chemise. According 65 to my improved method of manufacture, the same is of very simple construction, being wholly composed of two pieces of fabric, one of which is disclosed at 1 in Figure 1 and the other being disclosed at 2 in Figure 2. 70

The main body portion is disclosed at 1 in Figure 1. It will be seen that the same is of rough polygonal shape having lower edges 3 and 4 diverging upward and outwardly from a lower central pointed terminal 5. 75 These edges 3 and 4 extend upwardly and outwardly and terminate at pointed side ends 6 and 7 from whence converging side edges 8 and 9 extend inwardly and terminate at points 10 and 11, the line between these 80 points constituting the waist line of the garment. That portion of the fabric section 1 which is substantially diamond-shaped and which extends downwardly from the points 10 and 11 constitutes a front lower skirt portion, a similar back portion being provided by the section 2 as hereafter explained. 85

At positions above the points 10 and 11 are provided laterally extending side flaps or wings 12 and 13 which in the construction of the garment are folded inwardly or toward one another on the dotted lines 14 and 15. The fabric located between these lines 14 and 15 and designated by the numeral 40' constitutes the front upper panel of the 90 trunk portion of the garment.

When the blank is folded on the lines 14 and 15 as disclosed in Figure 4, it will be seen that the larger wing 13 which forms a part of the back of the trunk of the garment, pro- 100

- vides a lower central point 16 that is located on the center line of the garment and from which extends upwardly diverging lower edges 17 and 18, these edges terminating at 5 the points 10 and 11 located on the waist line of the garment. The upper edge of the wing 13 is disclosed at 19 and the same extends diagonally from the waist line point 10 to the diagonally opposite top edge of the garment. 10 When the small wing 12 is folded inwardly on the line 15, its lower diagonal edge 20 extends co-extensively and lies adjacent to the upper diagonal edge 19 on the wing 13. These two edges 19 and 20 are seamed together as by the stitching 21. This short 15 diagonal seam 21 that extends from the lower end of the edge 19 to a mid-way point on said edge is all that is required to produce the tubular trunk portion of the garment.
- 20 As will be seen in Figures 1 and 2, the two sections of fabric which make up the garment are so arranged that the warp and weft threads of the fabric extend parallel to the cut edges, so that when these two sections of 25 fabric are assembled together to form the finished product, the entire garment is made of fabric which is cut on the bias with respect to the longitudinal axis of the garment and the seams in the garment extend diagonally 30 across the garment. The blank or body portion 1 is provided with a suitably shaped upper edge 22 to form the front top edge of the garment. To complete the assembly of the garment, the angular section of fabric 2, 35 forming the rear skirted portion, is set in position with its top divergent edges 23 and 24 extending co-extensively and adjacent to the lower edges 17 and 18 on the wing 13. Then the edge 24 is stitched to the edge 17 to 40 provide the seam 25 and correspondingly the edge 23 is stitched to the adjacent edge 18 on the flap 13, this operation resulting in the formation of the seam 26. (See Figure 4.) Thereafter, the side edges 27 and 28 on the 45 fabric section 2 are seamed to the edges 8 and 9 of the blank 1 resulting in the side seams 29 and 30.
- If the garment is intended to be worn as an envelope chemise, the lower pointed terminal 5 on the main or body portion 1 may be overlapped with the similar lower pointed terminal 31 on the fabric piece 2 and these overlapped parts secured together by a button 32 engaging with a button hole 33 as is shown 50 in Figure 5, or by any other suitable detachable fastening means.
- It will be seen that the garment produced as herein described has the very desirable feature of a completely seamless front. The back 55 of the garment is provided with comparatively few seams so that the complete assembly of the garment requires but a few minutes work. In order to render the garment completely 60 symmetrical, a "blind" seam 34 may be utilized as shown in Figure 4 to provide a dia-

mond-shaped figure at the rear of the garment. Shoulder straps 35 of the conventional form may be secured to the top edge of the garment to support it on the wearer.

In the structure disclosed in Figures 6 to 9 inclusive, a garment is shown which is similar in all respects to that disclosed in Figures 1 to 5 inclusive, except that instead of having the lower diamond-shaped portion providing a bifurcated garment when the lowermost terminals are overlapped and detachably joined, I provide a lower skirted portion 36 so that the garment can be used as an underslip, or as an outer garment. The numerals of reference applied to the structure shown in Figures 6 to 9 inclusive correspond to those applied to similar parts in Figures 1 to 5 inclusive, with the exception of the skirt portion which I designate as 36. This skirt portion has long side edges 37 and 38 and a curved lower edge 39. The inserted piece forming the back of the skirt is disclosed at 40 and its upper diverging edges 41 and 42 are stitched to the edges 17 and 18 of the side wing 13 as by the seams 25 and 26 in precisely the same manner as was described with respect to the structure shown in Figures 1 to 5 inclusive. The side edges of the rear skirt section 40, which are indicated at 43 and 44 are stitched to the edges 37 and 38 on the front skirt portion as indicated by the seams 45 and 46 in Figure 8.

The fabric used in constructing the garment disclosed in Figures 6 to 9 is, in the completed garment, cut on the bias with respect to the longitudinal axis of the garment so that elasticity is imparted to the garment and the same smoothly and snugly fits persons of different bodily contour without requiring extensive alterations in the garment. The garment, because of this wholly bias-cut construction is rendered more or less wrinkleless and is extremely smooth fitting, permitting snug-fitting outer garments to be worn should the garments of my improved construction be worn in the nature of undergarments.

When the garment shown in Figures 6 to 9 inclusive is worn as an outer garment, it will be found to smoothly conform to the body of the wearer and afford a perfect fit by reason of its elastic construction and its freedom from a plurality of seams and inserted pieces which must commonly be employed in garments of the usual construction.

While I have herein described the lower dependent portions on the forms of garments disclosed by me as "skirts" or "skirted" portions, it will be understood that by such terms I may well mean any bifurcated, skirted or other appendages that may aptly be attached to the lower edges of the trunk portion produced in the simple fashion herein described.

What I claim is:-

1. A garment composed of a section of fabric forming the entire front of the garment,

said section having integrally formed flaps which extend inwardly toward one another and meet at the back of the garment, the front section of the garment having a lower flared 5 portion, and a fabric section corresponding in shape to said flared portion and having its upper edge secured to the lower edge of one of the flaps and having its side edges attached to the side edges on the lower flared portion 10 formed on the front section.

2. A garment having a trunk portion provided with a tapered end, said tapered end being inwardly folded across the weave of the fabric, said trunk portion being provided 15 with a flap also folded across the fabric weave, said flap when folded extending diagonally downward across the fabric and having one of its edges meeting an edge on the tapered end and seamed thereto.

20 3. In a garment, a body portion forming the trunk of the garment, said body portion being folded on spaced lines to provide a pair of inwardly extending parts which form the back of the garment trunk portion, the edges 25 of said inwardly folded parts meeting on a diagonally extending line and seamed together, one of said parts being larger than the other part, said larger part having an angularly extending lower edge.

30 4. A garment trunk portion composed of a sheet of fabric shaped to form the entire front of the trunk portion, said sheet being composed of bias fabric, said sheet being provided with a large back flap and a small back 35 flap located oppositely to the large flap, said large back flap extending diagonally downward across the rear of the trunk portion and having its lower edge so shaped that said edge diverges from a central low point to the opposite side edges of the trunk portion, the 40 smaller flap having one of its edges meeting an edge of the larger flap on a diagonal line and seamed thereto whereby the entire garment trunk portion is maintained by this 45 single seam.

5. In a garment, a trunk portion having a fabric section forming a seamless front member for said trunk portion, said fabric section having integral wings extending from it to 50 form the back of the garment trunk portion, one of said wings extending diagonally across the trunk portion, the lower edge of said diagonally extending wing diverging from a central point located on the median line of 55 the trunk portion to points higher up on the trunk portion and located at its opposite sides.

6. In a garment, a trunk portion having a fabric section forming a seamless front member for said trunk portion, said fabric section having wings which extend from it to form the back of the trunk portion, one of said wings being larger than the other, the edges 60 of said wings meeting on a diagonally extending line and being seamed together on

said line, the larger of said wings having its lower edge extending diagonally downward from one of the sides of the trunk portion of the garment to the central line thereof and thence extending diagonally upward to the opposite side of the trunk portion of the 70 garment.

7. A garment formed from a sheet of fabric having cut edges disposed parallel to the weave of the fabric, said sheet having a part forming a trunk front portion, flaps extending from said sheet and forming the trunk back portion, said flaps meeting on a diagonal line and having their meeting edges seamed together, an integral lower flared continuation formed on the trunk front portion, said continuation extending below the lower edges of the flaps, and a flared fabric section secured to the lower edge of one of the flaps and seamed to the sides of the flared continuation. 75

8. In an article of wearing apparel, a trunk portion consisting of a sheet of fabric having its threads on the bias with respect to the body of the trunk portion formed thereby, said sheet having its ends infolded and meeting on a diagonal line at the back of the trunk portion and stitched together. 80

Signed at the city, county and State of New York, this 20th day of March, 1930.

RUTH F. ALBERT.
